UNITED STATES PATENT OFFICE.

ALBERT HUNTER, OF PORTLAND, OREGON.

HOLDER-ON.

1,341,370.

Specification of Letters Patent.

Patented May 25, 1920.

Application filed May 6, 1919. Serial No. 295,229.

To all whom it may concern:

Be it known that I, ALBERT HUNTER, a citizen of the United States, residing at Portland, in the county of Multnomah and 5 State of Oregon, have invented certain new and useful Improvements in Holders-On, of which the following is a specification.

The present invention relates to improvements in holders-on for pneumatic tools, or 10 for use in combination with riveting hammers of the air type and this holder-on is designed for the purpose of backing up rivets when driven by long-stroke hammers of the well known type. 15 The subject matter of the present invention, although not confined solely for the purpose, is specifically adapted for use in ship construction when operating on the metal plates of the hull and other portions 20 of the vessel.

The invention consists essentially in the novel combinations and arrangements with the usual type of holder-on using air or where the ordinary heading is used, and consists of an extensible holder-on shaft that is 25 adjustable to suit the space between the part to be riveted and a fixed or stationary element against which the holder-on may be placed to back up the tool while the rivet 30 operation is being performed.

In the accompanying drawing one complete example of the physical embodiment of the invention is illustrated, the parts being constructed and combined according to 35 the best mode so far devised, for the practical application of the principles of the invention.

Figure 1 is a side view in elevation of an air driven holder-on or pneumatic tool of 40 the usual type equipped with the extensible shaft of the present invention.

Fig. 2 is an enlarged detail view partly broken away for convenience of illustration of the invention as embodied in the device 45 to be described.

Fig. 3 is a cross section taken on the lines 3—3 of Fig. 2.

In order to fully illustrate the invention as depicted in the drawing a standard form 50 of holder-on tool 1 of the pneumatic type is shown, which may be used for applying a hammer blow to the head of the rivet by causing a reciprocating piston to come into play, thus counter-acting the tendency of 55 the pneumatic riveter at the other end of

the rivet to drive the rivet back out of its place. This tool is equipped with the usual air connection 2 and the threaded tapered thimble 3 by means of which the holder-on is attached to the extensible shaft 4. 60

The device of the invention includes a screw bar 4 of suitable dimensions and weight and is screw threaded at one end to be entered and secured in the complementary thimble of the holder-on tool, and the 65 device also includes the extension bar 5 that telescopes over the screw bar and is adjustable thereon longitudinally. The extension bar is preferably a hollow or tubular member as a metallic pipe and is 70 equipped with the threaded head 6 with threads complementary to those upon the bar 4 and these two parts may be extended or collapsed in their relation with each other by turning the extension bar in the proper 75 direction, the extension bar being equipped on its lower end with the usual tool point 7 held fixed by the set screw 8. To provide means to hold the complementary parts 4 and 5 in fixed position a spring supported 80 pin 9 is disposed in the opening 10 through the wall of the extension bar 5 and will register with a longitudinal groove 11 cut lengthwise of the screw bar. The supporting spring 12 for the pin 9 is secured to the 85 extensible member 5 in any suitable means, here shown with the screw, and the spring 12 normally exerts an outward pressure to keep the pin 9 withdrawn.

When an adjustment has been made the 90 pin is inserted and held in position to prevent turning of the screw bar, or the extension bar by means of a spring keeper 13 which is held adjusted in a groove 14 in the extensible member. The keeper spring is 95 provided with an outwardly turned end 15 to allow it to ride up on the back of the pin 9. A slight turn past this point will serve to keep the pin in place during operation of the tool. Upon the opposite side of the extensible bar is a second spring supported pin 16 carried on the spring arm 17 and this spring arm normally causes an inward pressure on the pin. At the base of the screw in one of the grooves is a drilled hole 18 100 adapted to receive the pin 16 whenever the tool is extended to its limit thus locking and preventing further movement of the screw bar or extensible member. In normal working position the pin 16 will ride in the 110

bottom of the thread and will not otherwise affect the operation of the extension bar except to prevent it going past its limit.

In Fig. 1 the invention illustrates the holder-on in position for use on a ship's bottom supported upon the extensible holder and the extensible holder being supported by the block 19, the implement being arranged for use in a vertical position so that the rivet set of the tool may be alined with the rivet head to be held. Where the necessity for using the tool in a horizontal or angular position arises, the tool is backed up against the bracing or against the members of the shipway. The extensible holder-on is adjusted to approximately the space to be occupied and of course provision is made for forcing the rivet set or head to the rivet and it will be readily apparent that the extension member when in proper position will perform the function of backing up the tool with efficiency and satisfaction. From the

above description taken in connection with the drawings it is evident that I have provided a device that fulfils conditions of a 25 comparatively perfect extensible holder-on bar for this purpose as embodied in the following claim.

Having thus fully described my invention what I claim as new and desire to secure by 30 Letters Patent is:—

The combination with a rivet tool and its threaded screw bar having a longitudinal groove thereon, of a hollow internally threaded extension bar, a spring supported pin thereon for engaging the longitudinal groove of the screw bar, means for locking the pin in an engaged position, a second spring supported pin engaging the screw bar to limit the extension, a tool point on the lower end of the extension bar, and means for holding it in adjusted position.

In testimony whereof I affix my signature.
ALBERT HUNTER.
